UNITED STATES PATENT OFFICE

ABRAHAM NOVICK, OF NEW YORK, N. Y., ASSIGNOR, BY MESNE ASSIGNMENTS, TO
UNITED STATES ENVELOPE COMPANY, OF SPRINGFIELD, MASSACHUSETTS,
A CORPORATION OF MAINE.

ENVELOP-MACHINE.

1,328,011.

Specification of Letters Patent. Patented Jan. 13, 1920.

Application filed February 10, 1915. Serial No. 7,268.

To all whom it may concern:

Be it known that I, ABRAHAM NOVICK, a citizen of the United States, and a resident of the city of New York, county of Kings, 5 and State of New York, have invented certain new and useful Improvements in Envelop-Machines, of which the following is a specification.

This invention relates to machines for 10 making what are known as open window envelopes having a transparent patch applied thereto, and is particularly applicable to machines which make the complete envelop from a roll of paper.

15 The object of this invention is to provide means which will apply a patch to a blank while said blank is at rest in combination with rotary means for advancing the blank to the patch applying mechanism. A further 20 object of this invention is to provide mechanism for cutting a blank from a roll of paper, advancing said blank to the patch applying means and applying the patch as above described.

25 To accomplish the aforesaid objects, I find it best to stop the blank during the patch applying operation by the means shown in their preferred forms in the accompanying drawings, which illustrate also 30 all the mechanism required for the attainment of the objects stated.

In the drawings, Figure 1 is a plan view 35 of one form of the blank advancing and patch applying mechanism. Fig. 2 is a front view of Fig. 1 after the nearer frame only has been removed, thus allowing the gearing and other operating connections to be shown. Fig. 3 is a plan view of one form of machine for cutting the blanks and applying the 40 patch thereto, and Fig. 4 is a front view similar to Fig. 2, of Fig. 3. Figs. 5 and 6 are respectively views of another form of blank and envelop to which my invention can be adapted. Fig. 7 is a plan view with

45 some of the parts removed of a modification of the patch applying means shown in Fig. 1 and Fig. 8 is a front view similar to Fig. 2, of Fig. 7. Fig. 9 is an enlarged perspective view of the guide and knife blade shown in 50 Fig. 8. Fig. 10 is a plan view of the actuating mechanism following the rotating means shown in Figs. 11 and 12 for turning a parallelogrammic blank. Fig. 11 is a plan view of the mechanism for cutting and ro-

tating a blank, parallelogrammic in outline, 55 and the means for advancing the blank to the patch applying mechanism and Fig. 12 is a partial vertical section and front view of the same, said section being taken along the line C—C of Fig. 11. Fig. 13 is a perspective view of the window cutter showing 60 construction thereof.

My invention is peculiarly adapted to that type of machine best designated as a semi-rotary machine, that is, one in which the 65 blank is successively continuously forwarded by suitable rolls, and brought to a full stop to have certain operations performed thereon. This type of machine combines the advantages of simplicity, speed of operation 70 and accuracy in carrying out the steps necessary to make a complete envelop. Blanks of the shape shown in Figs. 3, 5 and 11 may be cut by revoluble cutters in the machine, (Figs. 3 and 11) from a roll of paper and 75 then advanced to the patch applying means, or suitable blanks already cut may be fed to said patch applying means by any of the feeding devices well known in the art, and which devices are not shown in the drawings. 80

The blank cut by the mechanism shown in Figs. 11 and 12 is of the form well known in the art, being substantially parallelogrammic in outline, thereby economizing 85 in paper. The feeding mechanism comprises feed rolls 26 and 27 on shafts 42 and 43 respectively, mounted in frames 1 and 2, said feed rolls coacting to advance the web of paper 63, which is supplied from a suitably 90 supported roll of paper not shown. Revoluble cylinder 28 on shaft 44 carries the four cutters 67, 68, 69 and 70 for making the edge cuts in web 63. Said cylinder 28 also carries center cutter 66 when said cutter is 95 needed, and window cutter 134, the severing cutters 71 being placed on roll 30 mounted on shaft 49.

Revoluble chip gripper rolls as 60 and 61 on shafts 47 and 48 respectively are prefer- 100 ably used to carry away the chips cut from the web and are caused to release said chips by suitable mechanism said chips being withdrawn by a suction pipe or other suitable mechanism not shown, or dropped into 105 a receptacle provided therefor. The cutting mechanism shown in Figs. 11 and 12 differs from that shown in Figs. 3 and 4 only

as regards the shape of the blank shaping and blank severing cutters and the description given above will suffice for both.

Referring now particularly to Figs. 11 and 12, segmental cylindrical roll 32 on shaft 51 coacts with roll 33 on shaft 52 for advancing the cut blank. Short cylindrical segmental blank advancing roll 34 on shaft 53 is placed as close as is permissible to conical rolls 40 and 41 on shafts 55 and 56 respectively without interfering therewith, and coacts with revoluble roll 35 on shaft 54. Said segmental rolls 32 and 34 are cut away in order to coöperate to continuously 15 advance the blank without interfering with the rotation of said blank by the conical rolls. Said conical rolls are partially cut away to prevent interference with the advance of blank 65 by segmental rolls 32 and 20 34 and the forwarding rolls following said conical rolls. The line of tangency of said conical segmental blank rotating rolls 40 and 41 is preferably in the plane of advance of the blank, said plane being preferably 25 horizontal, the axes of said rolls therefore converging so that shaft 55 carrying roll 40 must be terminated at some point preceding the intersection of the axes of said rolls, the shape of which is preferably that of frustra 30 of cones. Stand 62 placed in advance of the intersection of the axes of said conical rolls supports shafts 55 and 56 placed diagonally of the machine and inclined downwardly and upwardly respectively. Supports 64 35 and 84 are also provided near the extremities of shafts 55 and 56.

Short segmental blank forwarding roll 36 on shaft 58 coacts with revoluble roll 37, both of said rolls being placed as close as 40 is permissible to conical rolls 40 and 41 without interfering therewith, said rolls 36 and 37 coacting to grip blank 65 when the conical rolls release their hold, to advance the blank without interfering with the rotation 45 of the blank. Segmental roll 38 co-acts with revoluble roll 39 for advancing the blank to the patch applying means and is so geared and of such diameter as to increase the speed of travel of the blank to 50 allow time for the stopping of said blank later for the further operation thereon as hereinafter described. Said roll 38 acts in the same manner and has the same function in Fig. 11 and in Fig. 3, and the description 55 given applies to both figures.

The operating mechanism of the parallelogrammic blank cutting machine is as follows: pulley 3, obtaining power from a source not shown is mounted on shaft 42 as 60 is gear 4, which drives gear 5 on shaft 46. Cutter carrying cylinders 28 and 30, chip gripper roll 60 and segmental rolls 32 and 34 together with the rolls coacting therewith, are driven by gear 5, through the train of 65 gears, 6, 7, 8, 9, 10, 11, 12, 13 and 14, to-

gether with suitable gears not shown. Conical roll 41 is driven from bevel gear 20 on shaft 46, supported in frames 1 and 2 and stand 83, through bevel gears 21 and 25 on shaft 56, supported in stands 84, 62 and 64. Conical roll 40 is driven from bevel gear 25 through bevel gear 24 on shaft 55 supported in stands 64 and 62. Segmental forwarding roll 36 together with the roll coacting therewith are driven from bevel gear 22 on the end of shaft 46 through bevel gear 23 on shaft 57 supported in frames 81 and 82, and gear 15 on the same shaft through the train of gears 15, 155, 154, 152, 151 and 310 acting together with suitable gears not shown. 75

The conical rolls 40 and 41 are used to turn the blank 65 from the skewed position in which it is cut from the web 63 into the proper position for easy further operation thereon, such as patch applying, folding and gumming. In connection with the cutting mechanism described above, the patch applying means shown in Figs. 1 and 2 or Figs. 7 and 8 may be used, as shown in Figs. 3 and 4. 80

Referring to Figs. 1 and 2, forwarding rolls 135 and 136 take hold of the blank after it has been severed from the web and properly speeded up, or after it has been fed to said forwarding rolls by a suitable 90 feeding device not shown. Said rolls 135 and 136 are mounted on shafts 209 and 210 respectively supported in frames 81 and 82. Roll 85 carrying gumming ledge 137 for gumming around the window of the blank, 100 is mounted on shaft 212 and coacts with belt roll 86 on shaft 213, said belt roll carrying belts 94 adapted to carry the blank without interfering with the patch applying operation. Gum is supplied to gumming ledge 105 137 by gum roller 130 revolving in gum box 129. Plate 95 is supported on rods 126 mounted in the side frames 81 and 82 and is positioned directly under belts 94 to support the blank during the application of 110 the patch. Oscillatory alining stops 127 on shaft 223 are timed to engage the leading corners of the blank to stop and properly aline said blank, after which oscillatory presser feet 87 mounted on shaft 205 come 115 down on and hold the blank stationary on the belts 94, until the patch has been applied and the blank is ready to be advanced again. The hopper 139, holding a pile of cut patches 131, and comprising plate 96 having attached thereto rods 97 with toes 138 at the lower end of said rods to support the pile of patches, is supported by a bar 98 bent at right angles and having a dovetail shaped portion to fit a dovetail slot in frame 82, said 125 bar 98 and the hopper 139 attached thereto being given a reciprocating vertical motion as hereinafter set forth. Segmental roll 89 on shaft 218 coacting with roll 90 on shaft 217, is timed to grip the leading flap of the blank 130

when said blank is released by presser feet 87. Roll 90 carries belts 94 and with segment 89 advances the blank for further operation thereon, such as the gumming of the 5 bottom seam. Strips of gum are preferably placed on the under side of the side flaps by gumming ledges 106 on roll 91 mounted on shaft 220, said ledges 106 receiving the gum from gum roller 122 on shaft 222, said 10 gum roller rotating in gum box 128. Disks as 93 on same roll 91 coacts with roll 92 on shaft 221 for advancing the blank continuously to suitable mechanism for completing the envelop, as for instance folding devices, 15 shown conventionally in Fig. 1.

For the hopper 139 and the pile of cut patches 131 may be substituted the roll of paper 140 and suitable means for feeding and applying a strip of said roll. (Figs. 7 20 and 8). Rolls 141 and 142 on shafts 143 and 144 respectively, intermittently feed the paper over guide 147 having an upwardly inclined cutting edge 148 and supported to the side frames by rod 149, said paper passing 25 under blade 150, which is supported in a manner similar to hopper 139 by a bar similar to bar 98, as 298. Edge 148 and the edge of blade 150 are positioned in the same vertical plane so that a downward movement of blade 150 shears off a strip of paper 30 and carries said cut strip down to the blank, which is positioned with the gummed window under blade 150, whereby said strip is pasted over said window.

The actuating means for the blank advancing and patch applying mechanism is as follows: Segmental advancing roll and speeding up gear 154, which is driven from another part of the machine through gears 40 151, and 152 (Fig. 3) and gear 155 (Fig. 10), in turn drives forwarding roll gear 109. Through the latter rotation is transmitted to the gear 110 of the coating roll on shaft 210. Gumming roll 85 is driven through 45 gears 111, 113 and 112, while rolls 89, 90 91 and 92 are driven by the train of gears 114, 115, 116, 117, 118, 119, 120 and 121. The oscillatory motion of presser feet 87 is obtained through cam 103 on intermediate shaft 50 214, said cam rocking shaft 205 through roller 104 and link 105. Stops 127 on hub 88 and operating in slots 99 of plate 95 are given their oscillatory movement by cam 125 on shaft 218 through roller 124 and link 123 55 attached to shaft 223. The reciprocating motion of hopper 139 and of knife blade 150, is obtained through rollers 101 and 132 at the end of bars 98 and 298 respectively, said rollers being operated by cam 102 on shaft 215. The intermittent motion of rollers 141 60 and 142 is given by ratchet wheel 145 on shaft 143 through pawl 146 operated by forked lever 157 having a roller 133 actuated by cam 156 on shaft 216.

65 It is evident that the shape of the blank

shaping and severing cutters may be varied and depends on the shape of the blank to be cut and I therefore do not wish to limit myself to the shape of blank shown herein. It is also obvious that the blank cutting mechanism may be entirely omitted and a device for feeding cut blanks may be substituted without departing from the scope of my invention. 70

The operation of my improved machine 75 is as follows: Blank 65, after being cut by suitable mechanism and speeded up by segment 38 is passed on to the forwarding rolls 135 and 136 which advance said blank to gumming roll 85, where a strip of gum is 80 applied around the window of the blank, and the blank passed on to the belts 94. Said belts carry the blank forward to engagement with alining stops 127, which are timed to oscillate downwardly to engage the leading flap of the blank. The belts 94 cause the blank to tend to move forward, the blank thereby adjusting itself until stops 127 engage the leading corners of the blank, when the blank can no longer slip and is therefore properly alined. The blank is held at rest on to the belts in its alined position by the oscillatory presser feet 87, which come down on the blank and hold said blank stationary just as stops 127 move away from 90 the blank corners. Said blank is held stationary while hopper 139 or blade 150 come down over the gummed opening with the pile of patches 131 or the cut strip of paper respectively. In the case of the pile of 95 patches 131, the last patch will adhere to the gummed surface, and on the upward movement of the hopper, will be drawn out from toes 138 of rods 97 and separated from the remainder of said pile. Presser feet 87 100 are now raised, allowing the blank to be continuously forwarded by segmental roll 89, which is timed to grip the blank just as said presser feet let go. Said blank may now be continuously advanced to the bottom 105 110 seam gummer 91 and to any other mechanism for further operating thereon.

What I claim is:

1. In an envelop machine, the combination of means for continuously advancing a 115 web of paper, means for cutting an apertured window envelop blank from said web during the continuous advancement of said web, means for continuously advancing the blank for further operation thereon, means 120 for stopping and squaring the position of said blank, means for applying a patch to the aperture of said blank while said blank is at rest, means for holding said blank at rest until said patch has been applied and 125 rolls for continuously forwarding said blank after the patch has been applied.

2. In an envelop machine, the combination of means for continuously advancing a 130 web of paper, means for cutting an apertured

4

window envelop blank from said web during the continuous advancement of said web, means for continuously advancing said blank, means for stopping and squaring the position of said blank, reciprocating means for applying a patch to the aperture of said blank while said blank is at rest, a presser foot for holding said blank at rest while said patch is being applied, rolls for continuously forwarding said blank after the application of said patch and means for gumming the bottom seam of said blank.

3. In an envelop machine, the combination of means for continuously advancing a web of paper, means for cutting an apertured window envelop blank from said web during the continuous advancement of said web, means for continuously advancing said blank for further operation thereon, means for gumming around the window of said blank, means for stopping and squaring the position of said blank, means for holding said blank at rest, means for applying a patch to the aperture of said blank while said blank is at rest, means for continuously forwarding said blank after the patch has been applied and means for gumming the bottom seam of said blank.

4. In an envelop machine, the combination of means for continuously advancing blanks having windows cut therein, oscillatory means for stopping and alining successive blanks with the patch applying means, movable means for positively holding each blank at rest during the application of a patch to the window thereof and for releasing each blank after the patch has been applied, reciprocating means for applying a patch to said blank and rolls for forwarding said blank after the patch has been applied.

5. In an envelop machine, the combination of means for continuously advancing a web of paper, means for cutting chips from said web for forming open window blanks during the continuous advancement of said web, means for removing the chips from said web, rolls for continuously advancing said blank for further operation thereon, means for gumming around the window of said blank, means for stopping and alining said blank, means for alternately holding said blank at rest and releasing said blank, means for applying a patch to said blank while said blank is at rest, rolls for forwarding the blank after the patch has been applied, and means for gumming the bottom flap of said blank.

6. In an envelop machine, the combination of means for continuously advancing a web of paper, means for making blank shaping, window and severing cuts in said web during the continuous advancement of said web to form open window blanks, means for continuously advancing a blank for

further operation thereon, means for gumming around the window of said blank, means for stopping and alining said blank, means for alternately holding said blank at rest and releasing said blank, means for applying a patch to said blank while said blank is at rest, and rolls for forwarding said blank after the patch has been applied. 70

7. In an envelop machine, the combination of means for continuously advancing a web of paper, means for cutting an open window blank from said web during the continuous advancement of said web, means for continuously advancing said blank for further action thereon, means for gumming around the window of said blank, oscillatory stops for stopping and alining said blank, means for alternately holding said blank at rest and releasing said blank, means for applying a patch to said blank while said blank is at rest, rolls for forwarding said blank after the patch has been applied and means for gumming the bottom flap of said blank. 75

8. In an envelop machine, the combination of means for continuously advancing blanks each having a window cut therein, oscillatory stops for stopping and alining said blanks with the patch-applying means, reciprocating means for positively holding each blank at rest, reciprocating means for applying a patch to the window of each blank while said blank is at rest, rolls for continuously forwarding said blank after the patch has been applied, and means for gumming the flaps of said blank. 80

9. In an envelop machine, the combination of means for continuously advancing a web of paper, means for cutting open window blanks from said web during the continuous advancement of said web, means for continuously advancing a blank, oscillatory stops for stopping and alining a blank, an oscillatory presser foot for alternately holding said blank at rest and releasing said blank, means for applying a patch to said blank while said blank is at rest, rolls for forwarding said blank after the patch has been applied and means for gumming the bottom flap of said blank. 95

10. In an envelop machine, the combination of means for continuously advancing blanks having windows cut therein, oscillatory stops for stopping and alining a blank with the patch-applying means, an oscillatory presser foot for alternately holding said blank at rest and releasing said blank, reciprocating means for applying a cut patch to said blank, and rolls for forwarding said blank after the patch has been applied. 100

11. In an envelop machine, the combination of means for advancing a web of paper, means for making blank shaping window and severing cuts in said web during the continuous advancement of said web for forming window blanks, chip grippers for 105

- removing the chips from said web, means for continuously advancing a blank for further action thereon, means for gumming around the window of said blank, oscillatory stops for stopping and alining said blank, an oscillatory presser foot for alternately holding said blank at rest and releasing said blank, reciprocating means for applying a patch to said blank while said blank is at rest, rolls for forwarding the blank after the patch has been applied, and means for gumming the bottom flap of said blank during the last named forwarding.
12. In a machine for making window envelopes from a continuous strip of paper, in combination, rotary cutter means and coacting rotary die rolls for severing the web into rhomb shaped blanks, said blanks having two sides parallel to the path of the web and two sides diagonal to the side of said web, said blank having its major axis at an angle to its line of travel as it is severed from the web, means for thereafter advancing the blanks with their major axes normal to their subsequent direction of travel, means for cutting oblong window apertures in the blanks, said apertures extending parallel with the major axes of the blanks, means for gumming the aforesaid apertures, means for applying patches of transparent material over pre-cut window apertures and means for advancing the patched blanks to mechanism for performing subsequent operations thereon such as printing and folding.
13. In a machine for making window envelopes from a continuous strip of paper, in combination, coacting rotary cutter and rotary die means for severing the web and forming said web into rhomb shaped blanks, said blanks having two sides parallel to the sides of the web and other sides diagonal to said sides whereby the major axes of the blanks are at an angle to the line of travel of the blanks as they are severed from the web, means for thereafter adjusting the blanks to a position in which their major axes are normal to their direction of travel, means for thereafter advancing the blanks with their axes normal to their direction of travel, means for cutting oblong window apertures in said blanks, said apertures extending parallel to the major axes of the blanks, means for gumming the blanks about the apertures and means for applying transparent patches in register with the gummed portions of the blank to cover the said apertures, and means for performing subsequent operations on the blanks.
14. In a machine for making window envelopes from a continuous web of paper, in combination, coacting rotary cutters and rotary dies for cutting the said web into rhomb shaped envelop blanks, said blanks having their major axes at an angle to the line of travel of the web, means for advancing said blanks through mechanism for performing subsequent operations thereon, means adapted to receive the blanks as they come from the cutter devices and adapted to present the said blanks to said blank advancing means with the major axes of the said blanks normal to their direction of travel therein, means for cutting window apertures in the blanks, said apertures extending parallel to the major axes of the rhomb shaped blanks, means for gumming the said paper about said windows, means for applying and registering patches over the said windows, said patches being secured by the gum to the paper of the blanks; and means for performing subsequent operations on the blanks.
15. In a window envelop machine, in combination, means for continuously advancing a web of paper, a cutter means associated therewith and adapted to cut the said web into rhomb shaped envelop blanks, said blanks having their major axes at an angle to the sides of the web, means for continuously advancing the blanks as they come from the cutter devices and in the same relative position as in the web, a second blank advancing means, and means intermediate the first mentioned blank advancing means and said second mentioned blank advancing means adapted to receive blanks and to present the blanks with their major axes normal to their direction of travel in the second mentioned blank advancing means, means associated with the aforesaid means for cutting window apertures in the blanks, gumming the margins of the apertures and applying patches thereover, and means for delivering the patched blanks to mechanism for completing the folding of the envelop.
16. In a window envelop machine, in combination, means for successively advancing a series of rhomb shaped envelop blanks, said blanks being advanced with their major axes at an angle to their line of travel; a cutter means for successively cutting window apertures in the blanks; a chip remover adapted to remove the cut chip from the blanks and deliver the said chip to a chip conveyer; means for successively gumming the blanks; means for successively applying patches thereto; and means for subsequently performing further operations upon the patched blanks.
17. In a machine for making window envelopes, in combination with cutter means adapted to sever a web into a plurality of rhomb shaped blanks having their major axes angularly disposed with respect to their line of travel; blank advancing devices; means for receiving said blanks from the

cutter devices and for presenting the blanks to the aforesaid blank advancing devices with their major axes normal to their subsequent line of travel therein; a cutter means 5 adapted to cut window apertures in the blanks, a gummer adapted to gum the margins of the window apertures a patch supplying and applying device adapted to advance a length of patch paper from a supply roll, to sever the said paper into patches 10 of proper size, and to thereafter firmly

press the patch down upon the gummed blank and in registry with the window therein; and means for thereafter performing a series of subsequent operations on the 15 patched blanks whereby a complete envelop is formed.

ABRAHAM NOVICK.
